DESIGN FOR A SURGICAL CAMERA HOUSING

Gordon B. Pollock, South Laguna, Calif.

Application June 28, 1944, Serial No. 114,236

Term of patent 14 years

(Cl. D61—1)

To all whom it may concern:

Be it known that I, Gordon B. Pollock, a citizen of the United States of America, residing at South Laguna, in the county of Orange, State of California, have invented a new, original, and ornamental Design for a Surgical Camera Housing, of which the following is a specification, reference being had to the accompanying drawing, forming a part thereof:

Fig. 1 is a side elevational view of a surgical camera housing showing my new design;

Fig. 2 is a rear elevation thereof; and

Fig. 3 is a plan view thereof.

I claim:

The ornamental design for a surgical camera housing, substantially as shown.

GORDON B. POLLOCK.
